UNITED STATES PATENT OFFICE.

FRANK A. HALLECK, OF OAK PARK, ILLINOIS, ASSIGNOR TO SULLIVAN MACHINERY COMPANY, A CORPORATION OF MASSACHUSETTS.

FORGING MACHINE.

Application filed May 2, 1919. Serial No. 294,269.

This invention relates to forging machines and more especially though not exclusively to that type of forging machine used for forging drill steels or similar tools.

5 One object of the present invention is to provide an improved forging machine. Another object of the present invention is to provide a compact, light machine having a minimum number of projecting parts, and 10 one having also an improved clamping mechanism for holding a tool during the upsetting operations thereon. These and other objects and advantages of my improved construction will, however, hereinafter appear.

15 In the accompanying drawings, I have shown for purposes of illustration one embodiment which my invention may assume in practice.

In these drawings,

20 Fig. 1 is a longitudinal sectional view substantially on the line 1—1, Fig. 2, of my improved forging machine parts thereof being shown in side elevation.

Fig. 2 is a longitudinal sectional view substantially on the line 2—2 of Fig. 1, part of the forging machine being shown in side elevation.

In this illustrative construction I have shown a hollow base or casting 1 carrying a 30 swaging mechanism 2 and an upsetting mechanism 3, the latter being adapted to actuate a dolly 4 to upset the end of the steel held fixedly between a fixed jaw 5 and a movable jaw or head 6 of an improved 35 clamping mechanism.

The fixed jaw 5 of this clamping mechanism is preferably inclined at an acute angle, herein 45°, to the horizontal to provide a slanting face 7 on which a steel may 40 be guided into a die 8 carried by this jaw, this fixed jaw 5 being also preferably slanted as stated above so that when the movable jaw 6 is moved away therefrom, a free opening is provided at one side of the swaging 45 mechanism 2 to permit the insertion of a steel between the vise jaws. It will be noted that by having the face 7 slanting the die 8 will have a sufficient amount of substantially horizontal surface so that a steel can 50 rest thereon without additional aid. The movable vise jaw 6 carries a mating die 9, it being understood that the steel to be upset is firmly clamped between the dies 8 and 9 during the upsetting operation. The base 55 1 and the movable jaw 6 are herein shown

as also provided with another pair of clamping members 10 and 11 between which a tool may be clamped when it is desired to work on the tool by hand or by other instruments than the swaging or upsetting 60 mechanisms. However, it is understood that the clamping members 10 and 11 may be removed and a pair of shearing members substituted therefor, if it is desired to use the mechanism for cutting off the end of 65 stock.

The movable jaw 6 may be operated in a variety of ways but in the preferred form of my invention, I have shown a controlling lever 12 preferably formed integral with the 70 jaw 6, the lever and jaw being pivotally mounted on a stud shaft 13 carried by the frame, and the head 6 being rotatable through a movement of this lever to clamp a tool between either pair of jaws. In the 75 form of actuating means for the lever shown herein, I have provided a relatively large cylinder 14 in which is reciprocably mounted a large piston head 15 provided with a forwardly extending portion 16. The upper 80 part of the large piston or portion 16 preferably carries in a recess 17 formed therein a link 18 pivotally connected, as shown at 19, to the piston rod and pivotally connected, as shown at 20, to the lever. 85

If desired, the cylinder 14 may be of the double acting type having provision for admitting fluid pressure to both sides of the piston head 15 to move the latter in either direction, but I preferably admit pressure 90 fluid to but one face of the piston head 15 to move the piston to the right (see Fig. 1) and for this purpose, I provide an inlet pipe 21 for conducting pressure fluid to the rear end of the cylinder 15, the flow to this end 95 being controlled by suitable valve mechanism, not shown, preferably placed in the hollow base or casting 1. To provide for a return movement of the piston, I preferably form a cylinder chamber 22 in the 100 large piston rod 16 and place in this cylinder a fixed hollow piston rod 23 having a passageway 24 preferably provided axially therein, and, connected with an inlet pipe 25 which is preferably constantly supplied 105 with live pressure fluid which acts on the opposite faces 26, 27 of the cylinder 22 and piston rod 23, respectively, and tends to force the piston rod 16 to the left and normally retain the clamping members 10 and 110

11 in contact. This last named piston and cylinder further serve as a guiding means for the piston 16 so that it is not necessary to use a longer actuating means and thereby cause the cylinder 14 to project a greater distance beyond the base 1.

It will thus be seen that I have provided an exceedingly compact and light forging machine and that I have provided an improved clamping mechanism into which a steel is easily insertable, and further, that I have provided means for guiding the steel during the insertion thereof between the dies held by the respective vise jaws. It will also be noted that a very powerful clamping means is provided which is exceedingly light and may be easily and cheaply manufactured and which is easily controlled through the control of a simple valve mechanism in the base of the machine, and that one pair of clamping members is normally retained in clamping position.

While I have in this application specifically described one embodiment which my invention may assume in practice, it is to be understood that this form is used for illustrative purposes only and that the invention may be modified and embodied in various other forms without departing from its spirit or the scope of the appended claims.

What I claim as new and desire to secure by Letters Patent is:

1. A drill sharpener comprising clamping means including an inclined stationary jaw and a cooperating pivoted jaw whereby a work piece may be received by lateral movement thereof, and work performing means adapted to perform work on a member held by said clamping means in a direction parallel to the engaging surfaces thereof, said clamping means being adapted to support said member in position independently of any clamping effect.

2. A drill sharpener comprising clamping jaws one of which is pivoted whereby a work piece may be received by lateral movement thereof, said jaws meeting when closed on an inclined plane work performing means adapted to perform work on a member held by said jaws in a direction parallel to the engaging surface thereof, and means for allowing said member to rest in the position assumed during clamping operation of said jaws.

3. In a drill sharpener, a base, an inclined stationary vise jaw thereon, a vice jaw movable to provide a V-shaped opening between said jaws and having a depending lever, and means for moving said last named vice jaw and adapted to hold said latter jaw in a fixed relative position to said other jaw during normal operation and to provide a free opening to the space between said jaws, said means including a fluid pressure motor connected to said lever and adapted to ex-

ert a substantially horizontal actuating force, said jaws being operative to hold a work piece during hammering thereon in a direction parallel to the work engaging surfaces of said jaws.

4. In a drill sharpener, a base, an inclined stationary vise jaw thereon, a pivoted member carrying a vise jaw movable to provide a V-shaped opening between said jaws and having a depending lever, and means for moving said last named vise jaw and adapted to hold said latter jaw in fixed relative position to said other jaw during normal operation and to provide a free opening from above to the space between said jaws, said means including power means connected to said lever and adapted to exert a substantially horizontal force applied to said pivoted member at the side of the pivot thereof opposite said jaw.

5. In a drill sharpener, a base, a plurality of vise jaws thereon, a movable member having jaws alternatively engageable with said other jaws to form a plurality of pairs of jaws, said parts being constructed and arranged to permit a work piece to be inserted between either of the pairs of jaws so constituted by direct bodily movement in planes parallel to the lines of closure of the jaws and in a direction normal to the outer sides thereof.

6. In a drill sharpener, a base, a plurality of vise jaws thereon, a pivoted member having jaws alternatively engageable with said other jaws to form a plurality of pairs of jaws, said parts being constructed and arranged to permit a work piece to be inserted between either of the pairs of jaws so constituted by direct bodily movement in planes parallel to the lines of closure of the jaws and in a direction normal to the outer sides thereof.

7. In a drill sharpener, a base, a plurality of vise jaws thereon one of which is disposed at an acute angle to the horizontal, a movable member alternately engageable with said jaws, and means for maintaining said member in fixed relation to said jaws during normal operation.

8. In a drill sharpener, a base, a plurality of vise jaws thereon one of which is disposed at an acute angle to the horizontal, a pivoted member alternately engageable with said jaws, and means for maintaining said member in fixed relation to said jaws during normal operation.

9. In a drill sharpener, the combination comprising a hollow base, a stationary jaw carried thereby, a lever in said base pivotally mounted near the top thereof, a vise jaw cooperating with said other jaw and carried by said lever, and a single means for operating said lever to move said vise jaw and holding it in work clamping position.

10. In a drill sharpener, the combination

comprising a base, a stationary jaw carried thereby, a substantially vertically disposed lever pivotally mounted near the top of said base, a vise jaw cooperating with said other 5 jaw and connected to said lever, and power means operating said lever to move said vise jaw and holding the same in work clamping position.

11. A forging machine comprising a vertically disposed frame, a stationary jaw mounted at the upper portion thereof, a pivoted jaw having a depending lever, a cylinder carried by said frame and having its axis disposed in a substantially horizontal 15 plane and substantially at a right angle to said lever, a piston intermittently reciprocably mounted therein, and means for connecting said lever with said piston.

12. In a drill sharpener, the combination comprising a hollow base, vise jaws carried thereby, a lever therein pivotally mounted near the top thereof, a plurality of vise jaws cooperating with said other jaws and carried by said lever, and means for operating 25 said lever to move said vise jaws, said means also operating to hold said jaws in work clamping position.

13. In a drill sharpener, the combination comprising a base, vise jaws carried thereby, a substantially vertically disposed lever pivotally mounted near the top of said base, a plurality of vise jaws cooperating with said other jaws carried by said lever and disposed on opposite sides of the axial line of 35 said lever, and means for operating said lever to move said vise jaws, said means being adapted to hold said cooperating jaws in fixed relative positions during normal operation.

14. In a drill sharpener, the combination comprising a hollow base, vise jaws carried thereby, a lever therein pivotally mounted near the top thereof, two vise jaws cooperating with said other jaws and disposed on the opposite sides of said lever, and means for operating said lever, said means being adapted to hold said cooperating jaws in fixed relative positions during normal operation.

15. In a drill sharpener, the combination comprising a hollow base, a lever therein pivotally mounted near the top thereof, a plurality of vise jaws mounted on the base, a plurality of pivotally movable cooperating 55 vise jaws operatively connected to said lever, and means for operating the lever and for normally retaining one set of vise jaws closed.

16. In a drill sharpener, the combination comprising a hollow base, a pneumatic tool, a fixed vise jaw adjacent said tool, and a movable vise jaw movable to provide an upwardly opening space past said tool to the space between said jaws.

17. In a drill sharpener, the combination

comprising a base, a pneumatic tool, a fixed vise jaw adjacent said tool, a vise jaw pivotally movable to provide an upwardly opening space extending past said tool, means for supporting said tool whereby it may perform work on a member held by the jaws in a direction parallel to the engaging surfaces thereof, and means supporting a work piece in operative position when said jaws are opened.

18. In a drill sharpener, the combination comprising a base, a pneumatic tool, a fixed vise jaw adjacent said tool, a vise jaw movable to provide an upwardly opening space extending past said tool, means for supporting said tool whereby it may perform work on a member held by the jaws in a direction parallel to the engaging surfaces thereof, one of said vise jaws having a surface with a horizontal component, and means including a recess in said surface to receive a work piece, said recess being adapted to support a tool in position while said jaws are opened.

19. In a drill sharpener, the combination comprising a base, a pneumatic tool, a fixed vise jaw adjacent said tool, a pivotally vertically disposed vise jaw movable to provide an upwardly opening space extending past said tool, and means for supporting said tool whereby it may perform work on a member held by the jaws in a direction parallel to the engaging surfaces thereof.

20. In a drill sharpener, the combination comprising a substantially horizontally disposed fluid pressure actuating means, a jaw, a cooperating pivoted vise jaw, and means therebetween for operating said jaw by said actuating means.

21. In a drill sharpener, the combination comprising a substantially horizontally disposed fluid pressure actuating means, work holding means including a vertically inclined pivoted vise jaw, and means therebetween for operating said jaw by said actuating means.

22. In a drill sharpener, the combination comprising a substantially horizontally disposed fluid pressure actuating means, work holding means including a vertically inclined pivoted vise jaw, means therebetween for operating said jaw by said actuating means, and horizontally disposed work performing means operative on work clamped by said jaw.

23. In a drill sharpener, the combination comprising a substantially horizontally disposed fluid pressure actuating means, work holding means including a vertically inclined pivoted vise jaw, means therebetween for operating said jaw by said actuating means, and work performing means operative on work clamped by said jaws and disposed horizontally in the zone of the working surface of said jaws.

24. A mechanism comprising work clamping means including a pivoted jaw, actuating means therefor, and work performing means operative on work clamped by said clamping means, said actuating and work performing means having their axes disposed in substantially horizontal planes.
25. In a drill sharpener, the combination comprising a plurality of fixed vise jaws, a pivoted vise jaw carrier alternately engageable therewith, and actuating means therefor normally retaining one pair of said jaws in fixed engagement
26. In a drill sharpener, a hollow base, two fixed jaws thereon, a pivoted vise jaw carrier having a projecting lever extending into said hollow base, and a substantially horizontally disposed actuating means mounted in said hollow base and connected to said lever and having provision for normally retaining said carrier in contact with one of the fixed vise jaws.
27. In combination, in a drill sharpener, a pair of stationary jaws thereon, a jaw pivotally movable relative to said stationary jaws, operating means for said movable jaw comprising a lever connected to said jaw and a member cooperating with said lever having different areas on opposite sides thereof, and means for continuously supplying fluid pressure to one of said areas and intermittently to the other.
28. In combination, in a drill sharpener, a pair of stationary jaws thereon, a jaw movable relative to said stationary jaws and operating means for said movable jaw comprising a lever connected to said jaw, an actuating means for said lever comprising a cylinder, a piston therein, a bore in said piston and a stationary piston in said bore, and means for continuously admitting fluid pressure to said bore and for intermittently supplying fluid pressure to said first mentioned piston.
29. In combination, in a drill sharpener, a pair of stationary jaws thereon, a jaw movable relative to said stationary jaw and operating means for said movable jaw comprising a lever connected to said jaw, an actuating means for said lever comprising a cylinder, a piston therein, a bore in said piston, a stationary piston in said bore, and means for continuously admitting fluid pressure to said bore through said stationary piston and for intermittently supplying fluid pressure to said first mentioned piston.
30. In a clamping mechanism, a pivoted actuating element, a pair of stationary work engaging members on opposite sides of said pivot, a plurality of work engaging members carried by said actuating member, and means to maintain said latter members in fixed relation to said stationary work engaging members, said mechanism being constructed and arranged to permit the work to be freely moved in a direction normal to said pivot between the work engaging members when the latter are separated.
31. In a clamping mechanism, a pivoted actuating element, a pair of stationary work engaging members disposed on opposite sides of a vertical plane including the axis of the pivot of said element, a plurality of work engaging members carried by said actuating member, and means for maintaining said latter members in fixed relation to said stationary work engaging members.
32. In a drill sharpener, a base, a stationary vise jaw thereon, a movable vise jaw pivoted adjacent its upper end and having an elongated substantially vertically extending lower arm movable in a vertical plane to provide an opening between said jaws, and power means operatively connected to the lower end of said arm for moving said vise jaw to provide access to the space between said jaws.
33. In combination, clamping mechanism, actuating means therefor including a cylinder and piston, and means for supplying actuating fluid to one side of said piston including telescopic stationary and movable members cooperating with the piston and having pressure fluid chambers formed therein.
34. In combination, clamping mechanism, actuating means therefor including fluid operated means having a piston, and means for supplying actuating fluid to effect piston movement including a stationary element having a longitudinal fluid conducting passage and means carried by said piston surrounding and telescoping with said stationary element.
35. In combination, clamping mechanism, actuating means therefor including a piston, cylinder means therefor, and fluid conducting means communicating with the opposite sides of said piston, the means leading to one side thereof comprising hollow telescopic members.
36. In combination, clamping mechanism, actuating means therefor including a piston, cylinder means therefor, and fluid conducting means communicating with opposite sides of said piston, the means leading to one of said sides comprising stationary and movable telescopic members, said movable member projecting longitudinally away from said piston.
37. In combination, clamping mechanism, actuating means therefor including a cylinder, a piston therein, a longitudinal guide for said cylinder offset from the axis thereof, and means for supplying fluid to said cylinder through said piston.
38. In combination, clamping mechanism and actuating means therefor including a cylinder, a stationary piston therein, a longitudinal guide for said cylinder offset from

the axis thereof, and means for supplying fluid to said cylinder through said piston.

39. In combination, clamping mechanism, actuating means therefor including a plurality of cylinder and piston forming elements whose longitudinal axes are offset from each other, and a member movable relative to said piston and angularly disposed to said axes for connecting said clamping mechanism to said actuating means.

40. In combination, clamping mechanism, actuating means therefor including a plurality of cylinder and piston forming elements whose longitudinal axes are offset from each other, and operating connections between said clamping mechanism and said actuating means.

41. In combination, clamping mechanism, actuating means therefor including a piston and cylinder, telescopic members associated with said piston but offset from the axis thereof, and connections for said clamping

mechanism operatively connected to said piston including a pivoted element disposed substantially parallel to the axis of the offset members.

42. In combination, clamping mechanism, actuating means therefor including a piston and cylinder and telescopic members associated with said piston but offset from the axis thereof, and connections for said clamping mechanism operatively connected to said piston including a pivoted element transversely disposed relative to the axis of said piston.

43. In combination, clamping mechanism, actuating means therefor including a cylinder, a piston therein, a longitudinal guide for said piston offset from the axis thereof, and means for subjecting said piston to a force for moving the same including fluid supply means telescoping with said guide.

In testimony whereof I affix my signature.
